UNITED STATES PATENT OFFICE.

LEWIS J. BAZZONI, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

BUTTONING MACHINE.

Application filed March 1, 1920. Serial No. 362,543.

To all whom it may concern:

Be it known that I, LEWIS J. BAZZONI, a citizen of the United States, residing at Swampscott, in the county of Essex and State of Massachusetts, have invented certain Improvements in Buttoning Machines, of which the following description, in connection with the accompanying drawings is a specification, like reference characters on the drawings indicating like parts in the several figures.

This invention relates to buttoning machines. The invention is herein shown by way of illustration as embodied in a machine especially designed for buttoning gaiters or shoe uppers, although, in many of its aspects, the invention is not restricted to such use.

In the manufacture of button boots and shoes, it is the general practice to button a sufficient number of the lower buttons upon the shoe upper to hold the button piece and the buttonhole fly of the upper correctly positioned with respect to each other during the lasting and subsequent shoe making operations. After the shoe bottom has been attached it is customary to button a number of the lower buttons of the shoe in order that the shoe upper may be properly fitted and held, as, for example, to facilitate the treeing and ironing or other finishing operations upon the shoe. Similarly after the various making and finishing operations upon the shoe have been substantially or wholly completed, it is customary to button the shoe in the packing room preparatory to shipping.

The requirements of various buttoning operations such as those above mentioned vary widely due to differences in the condition of the work at different stages, affecting its presentation to buttoning instrumentalities and their operation upon the work, and to other factors such as the fact that differences in style as well as in size are of much more consequence when it is attempted to button all of the buttons of shoes in the packing room than when it is desired to button only a few of the lowermost buttons, primarily, because the widest and most noticeable variations in curvature as well as in button locations are encountered along the upper parts of the shoe tops. Furthermore, the problem of organizing a buttoning machine to operate satisfactorily upon a shoe after

the sole has been attached is radically different from the problem of buttoning a shoe upper in the fitting room.

The present invention has for a general object to provide a machine which may be employed for buttoning gaiters or shoe uppers and which will be equally well adapted for buttoning shoe uppers before attachment of the soles and for any buttoning operations which it may be desired or required to perform after the attachment of the shoe bottoms. In another aspect, the invention aims to provide a buttoning machine which will be relatively simple and economical in operation, require a minimum of effort and skill on the part of the operator, and be capable of operating on work of widely different characteristics with a minimum of adjustment.

To attain these and other general objects, the illustrative machine is organized to button successively all or as many of the buttons of a shoe upper or shoe as may be desired, the construction and arrangement herein shown being such that either right or left shoes or shoe uppers may be buttoned interchangeably without the necessity of any adjustment to adapt the machine for rights or lefts, or vice versa. This organization permits the use of a single set of work handling and buttoning instrumentalities, thereby obviating the necessity of complicated and expensive sets of instrumentalities for each buttoning operation as in the case of machines which perform a plurality of buttoning operations simultaneously and similarly eliminating the necessity of complicated adjustments of the different sets of instrumentalities for work of different characteristics. At the same time, the illustrated construction and arrangement provide for buttoning without especial adjustment of the machine any number of buttons beginning with either the lowermost or the topmost button.

In accordance with other important features of the invention claimed in a copending divisional application, Serial No. 704,519, filed April 5, 1924, the illustrative machine operates automatically, requiring no substantial care or attention on the part of the operator from the time that a piece of work is introduced into the machine until the work has been discharged from the machine. To increase the capacity of the ma-

chine and to enable the operator to introduce or prepare to introduce a succeeding gaiter or shoe upper before the completion of the operation upon a gaiter or shoe upper, the illustrative machine is organized to stop automatically after any desired predetermined number of buttoning operations have been performed. Preferably also, and as shown, the machine is provided with means for automatically resetting the mechanism which controls the automatic stopping of the machine such that until the controlling mechanism is readjusted, in the continued operation of the machine it will perform automatically in succession like series of buttoning operations.

Other features of the invention consist in novel means for feeding and positioning the button piece and buttonhole fly of a gaiter or shoe upper for the buttoning operations, and in novel means for preparing the buttonholes to facilitate the entrance of buttons therein and for relatively manipulating the buttons and buttonhole fly to effect the passage of the buttons through the buttonholes, as well as in means for minimizing the tension on the work.

Although the invention is illustrated as embodied in a machine designed to pass buttons successively through their buttonholes, it is to be understood that various features of the invention are not limited in applicability to machines of this type, but may be employed in machines of other types, including machines for buttoning a plurality of buttons substantially simultaneously. It is intended, therefore, that the scope of the claims shall be limited only as required by the prior art.

These and other objects and features of the invention, including features relating to various combinations and arrangements of parts, will be apparent from the following description and will be pointed out in the claims.

In the drawings,

Fig. 1 is a view in plan of a machine according to the invention, parts being broken away to reveal the operating mechanism of the machine;

Fig. 2 is a view in perspective of the buttoning instrumentalities looking from the front of the machine;

Fig. 3 is a view of the buttoning instrumentalities and the operating mechanism therefor seen from the rear of such instrumentalities;

Fig. 4 is a detail view of the buttoning instrumentalities taken from the front of the machine;

Fig. 5 is a plan view of the buttoning instrumentalities with the parts in position to begin the feeding of a button and the buttonhole fly;

Fig. 6 is a view similar to Fig. 5 showing

the parts substantially at the end of the operation of feeding the button and the buttonhole fly;

Fig. 7 is a detail of the button guide and the button feeder;

Fig. 8 is a plan view of the buttoning instrumentalities in the positions which they occupy at the completion of a buttoning operation;

Fig. 9 is a view of the mechanism shown in Fig. 8, looking from the rear and showing the parts in the positions they assume just previous to the passing of a button on a button piece into the corresponding buttonhole of the buttonhole fly;

Fig. 10 is a view of the buttoning instrumentalities looking from the front of the machine and showing the parts at the end of the operation of feeding the buttonhole fly;

Fig. 11 is a view similar to Fig. 10, showing the parts in the positions they occupy upon the passing of a button through a buttonhole;

Fig. 12 illustrates the operating mechanism for the buttoning instrumentalities which includes a clutch and controlling means for the clutch constructed to discontinue the operation of such instrumentalities after the performance of a predetermined number of buttoning operations;

Fig. 13 is a view of a portion of the mechanism shown in Fig. 12 including the clutch controlling means; and

Fig. 14 shows the clutch controlling means looking in the opposite direction.

The illustrated machine comprises generally buttoning instrumentalities designed to perform a series of buttoning operations one after another for inserting the buttons on a button piece successively into the buttonholes of a buttonhole fly and operating mechanism for the buttoning instrumentalities constructed to discontinue the operation of such instrumentalities after the performance of a predetermined number of buttoning operations. The buttoning instrumentalities, as shown, are particularly adapted for operation on the button piece and buttonhole fly of a shoe.

The machine frame comprises a bottom plate 2, see Fig. 12, provided with upright standards 4, to which is pivoted a cover plate or table 6 which carries the buttoning instrumentalities. A shell (not shown) interposed between the table 6 and bottom plate 2 encloses the operating mechanism of the machine.

In the illustrated construction, the buttoning instrumentalities include a button guide 8 having a curved slot 10, the curvature of which preferably approximates the average curvature of the lines defined by the buttons on the button pieces of the shoes to be operated upon. The slot 10 is made of a length to receive all of the buttons on a

button piece so that no manipulation of the buttons or of the button piece by the operator is necessary after the machine is started.

The button guide 8 is formed with a loop 11 communicating with the slot 10 and affording means whereby the buttons on a button piece may be introduced into the guide. The introduction of the buttons on a button piece into the slot of the guide is further facilitated by inclining the guide upwardly from its delivery end to the loop 11. The guide 8 is formed near its delivery end with a depressed portion 12 (see Fig. 4) for a purpose which will be hereinafter explained in connection with the description of the operation of the machine.

Means is provided for guiding a button-hole fly relatively to the button guide, and, in the illustrated exemplification of the invention, such means comprises a plate 13 formed integrally with the outer wall 14 of the button guide, see Fig. 3, and having an upwardly extending portion secured by a nut 215 to a stud 15 in a yoke 16 extending upwardly and forwardly from the cover plate 6. The plate 13 is so disposed as to position the buttonhole fly substantially at right angles to the plane of the guide 8, by which is meant a plane passing through the guide at right angles to the axes of the buttons in the slot 10, from which it follows that the buttonhole fly is also positioned substantially parallel to the axes of the buttons in the guide.

Co-operating with the button guide 8 at the delivery end of the slot 10 are means for passing the buttons in the guide into the buttonholes of a buttonhole fly and means for controlling the buttonhole fly during the insertion of the buttons into the buttonholes. As shown, a pusher 17 movable angularly of the slot 10 of the button guide, and supported in its movement by said guide, operates to pass the buttons into the buttonholes, and the controlling means for the buttonhole fly comprises fingers 18 and 19 disposed for engagement with the fly at opposite sides of a buttonhole presented in position to receive a button from the button guide. Although, in the illustrated construction, the pusher 17 is moved in a path oblique to the slot 10 of the button guide, it is evident that, if desired, it may be moved at right angles to such slot without departing from the principles of the invention. The fingers 18 and 19, by engagement with the fly on opposite sides of a buttonhole, serve to restrain the fly from movement in the direction of movement of a button in entering the buttonhole. The button pusher 17 is beveled at 277 for a purpose to be hereinafter set forth.

Preferably, the buttonhole into which a button is to be passed from the button guide is opened to facilitate the insertion of the

button. To this end, the finger 18 is disposed to co-act with the outer wall 14 of the guide to maintain the portion of the buttonhole fly rearwardly of the buttonhole stationary while the forward edge of the buttonhole and the material around the buttonhole are moved transversely of the fly across the delivery end of the slot 10. Preferably, and as shown, the transverse movement of the forward edge of the buttonhole is effected by the finger 19 in conjunction with a member 20 normally disposed across the end of the slot 10 but mounted for yielding movement away from the slot, the fingers 18 and 19 being so operated that the finger 18 is allowed to remain stationary after it has gripped the fly against the button guide while the movement of the finger 19 is continued to thrust the forward edge of the buttonhole and the member 20 across the slot. The opening of the buttonholes by movement of one of their edges transversely of the buttonhole fly possesses manifest advantages in that the buttonholes may thereby be opened easily and without appreciable strain on their edges, whereas the opening of a buttonhole by pushing back the edges of the buttonhole in the plane of the fly requires the exertion of a substantial force which imposes a correspondingly great strain on the edges of the buttonholes with consequent danger of tearing them. The finger 18 preferably contacts with the buttonhole fly at a point spaced from the edge of a buttonhole as indicated in Fig. 10, whereas the finger 19 is disposed to project slightly across the buttonhole opening. This arrangement of the fingers permits the rear edges of the buttonhole to flex outwardly to facilitate the insertion of a button into the buttonhole, and insures the complete opening of the buttonhole commensurate with the extent of movement of the finger 19. The manner of engagement of the finger 19 with the buttonhole fly not only causes the edge of the buttonhole to be pushed back to the full limit of movement of the finger thus opening the buttonhole to the maximum degree, but prevents injury to the fly such as might ensue if the finger was spaced from the edge of the buttonhole, by the bending of the edge of the buttonhole about the finger by the button in its passage into the buttonhole.

In the illustrated construction is embodied a simple and convenient means for operating the fingers 18 and 19, the finger 18 being pivoted between ears 22 on the finger 19 which, in turn, has its hub 23 fulcrumed on the stud 15 of the yoke 16. Projecting rearwardly from the hub 23 of the finger 19 is an arm 28 connected by a link 30 with a lever 32 fulcrumed at 34 to an upright 36 on the bottom plate 2 and deriving its motion from a roll 38 operated by a path cam 130

40 on the cam shaft 41 journaled in uprights on the bottom plate. A spring 42 connected to a rearward extension 44 of the finger 18 and to a lug 46 projecting from 5 the hub 23 of the finger 19 causes the finger 18 to partake normally of the movements of the finger 19, but permits the movement of the finger 18 to be discontinued after it has gripped the buttonhole piece against the 10 button guide while the movement of the finger 19 is continued to open the buttonhole. The member 20 is preferably formed integrally with a lever 48, also fulcrumed on the stud shaft 15, and a spring 50 seated 15 in opposed recesses formed in an enlarged portion of the lever 48 and in the forward side of the leg 49 of the yoke 16 respectively acts to project the member 20 normally across the end of the slot 10 of the guide, 20 the movement of the lever 48 under the impulse of said spring being limited by the engagement of an arm 52 upstanding from the hub of the lever with a lug on the forward side of the yoke 16. The arm 52 is 25 preferably formed so as to facilitate its manipulation by the hand of the operator to shift the member 20 away from the slot 10 thus enabling the operator to withdraw the buttons from the delivery end of the 30 slot whenever desired.

The provision of guiding means for the buttonhole fly disposed to position it substantially at right angles to the plane of the button guide and the construction and arrangement of the pusher 17 and the means for controlling the buttonhole fly and opening the buttonholes enables the lower button 35 on a button piece, sometimes referred to herein as the "throat" button, to be buttoned readily and reliably. With this construction, the buttonhole fly does not have to be drawn up over the button guide so as to locate the buttonhole over the button which would render it difficult, if not impossible 40 to present the buttonhole contiguous to the throat in proper position to receive the throat button. On the contrary, a buttonhole when in button receiving position is disposed substantially parallel to the axis 45 of the button. Such disposition of the buttonhole can be accomplished with the exertion of little tension on the buttonhole fly even when the buttonhole is located at a short distance only from the throat of a 50 shoe. The buttoning operation is further facilitated by inclining the outer wall 14 of the button guide inwardly to form a pointed end on the wall, disposed rearwardly of the end of the inner wall of the guide. Such a 55 construction reduces to a minimum the extent of movement of the forward edge of a buttonhole necessary to open the buttonhole. This is of particular importance with respect to the buttoning of the throat button, 60 since the portion of the buttonhole fly for-

wardly of the buttonhole can be flexed to a limited degree only inasmuch as it is confined on one side by its connection to the buttonhole fly above and below the buttonhole and on the other side by the seam which 70 secures the fly to the vamp of the shoe. The guide 13 for the buttonhole fly follows substantially the contour of the outer edge of the wall 14, and the heads of the buttons overlie the upper surfaces of the walls of 75 the button guide for some distance from the slot of the guide. The guide 13 is, however, prevented from interfering with the heads of the buttons by the provision of a slot 57, see Figs. 4 and 9, between the forward end 80 of the guide 13 and the wall 14 of the button guide, into which the lower portions of the outer sides of the buttons may project as they pass along the button guide.

In order to locate the buttons successively 85 for insertion by the pusher 17 and to present the buttonholes of the buttonhole fly in button receiving position intermediate between the paths of movement of the fingers 18 and 19, means is provided for feeding the buttons and the buttonhole fly. Preferably, and as shown, the button feeding means comprises a lever 58 pivoted on a stud shaft 60 journaled in bearings 63 and 64 extending upwardly from an arm 65 pivoted in a bracket 266 on the table 6 and a yoke 267 depending from said table. The forward end of the lever 58 is normally pressed downwardly on the guide by a spring 66 interposed between a lug 68 projecting rearwardly from the hub of the lever 58 and the arm 65 intermediate between the bearings 63 and 64. The forward end of the button feeding lever 58 is preferably recessed, see Fig. 7, to correspond substantially with the upper surface of a 100 round-headed button and is also curved upwardly at the rear of the button engaging recess as indicated at 169 for engagement by the beveled surface 277 of the pusher 17 to disengage the button feeder from the head of a 105 button prior to its engagement by the pusher.

The feeding means for the buttonhole fly is also preferably operated from the arm 65 and comprises a finger 70 pivotally secured 110 by a stud 71 to the under side of an angular extension 72 of the stud shaft 60 and normally pressed against the outer surface of the fly by a leaf spring 74. The arm 65 is operated forwardly and rearwardly toward 115 and from the delivery end of the slot 10 of the button guide. Upon the rearward movement of the arm, the recessed end of the button feeder 58 snaps over the top of the next 120 button to be fed, and the finger 70 engages 125 the buttonhole adjacent to that in which a button has just been inserted. In order to insure that the finger 70 will enter the buttonhole on its rearward movement, controlling means for the finger is provided con- 130

structed to aline the finger with the expanded portions of the buttonholes nearest the edge of the buttonhole fly. As shown, such means comprises a plate 76 secured to the 5 extension 72 adjacent to the stud 71 and having fins 78 and 80 depending from each side of its forward end for engagement with the outer and inner surfaces of the buttonhole fly respectively. The fin 80, as will appear 10 from Fig. 9 of the drawings, spaces the inner surface of the buttonhole fly slightly away from the button guide 8, thus causing the inner hooked end of the finger 70 which is adapted to contact with the guide to project 15 beyond the inner surface of the buttonhole fly so as firmly to engage the buttonholes of the fly. The guiding plate 13 is spaced from the outer wall 14 of the button guide forwardly of the rearward limit of 20 movement of the finger 70 by reason of the provision of the slot 57, Figs. 3 and 4, and the feeding finger in its rearward movement when there is no work in the machine rides on the upper edge of the wall 14. The finger 70 is received in a slot formed in the plate 76 forwardly of the fin 78, the plate being constructed to act as a stop for limiting 25 the inward movement of the finger 70 thereby preventing the finger from becoming 30 jammed in the slot 57. A spring 81 coiled about the stud shaft 60 tends to rotate said shaft and to urge the free end of the plate 76 downwardly upon the edge of the buttonhole fly. Accordingly, inasmuch 35 as the buttonholes are spaced substantially uniformly from the edge of the buttonhole piece, the plate 76 will always position the finger 70 accurately relatively to the buttonholes.

40 When a buttonhole is in button receiving position, its upper edge should be a little above the crown of the button. If, however, it was endeavored to dispose the buttonhole adjacent to the throat at the level of the 45 head of the corresponding button prior to the feeding of the buttonhole fly, see Fig. 4, the end of the outer wall 14 of the button guide would either engage the shoe across the seam between the button piece and the 50 vamp or the button piece close to the seam, depending upon the distance by which the button and buttonhole were spaced from the seam. In either case, the portion of the shoe contacting with the wall 14 would not flex 55 readily, thus making it difficult or impossible fully to elevate the buttonhole. Because of these considerations and with a view further to facilitate the feeding of the buttonhole fly, it is positioned normally with the 60 upper edges of the buttonholes below the tops of the heads of the buttons, as seen in Fig. 4, and, in order to present the buttonholes in proper button receiving position, the buttonhole fly is raised subsequent to or 65 during the final part of its feeding move-

ment. The raising of the buttonhole adjacent to the throat tends to raise the shoe including the button piece, but, by reason of the forward feeding of the button piece simultaneously with the feeding of the buttonhole fly, the button piece will contact with the outer wall of the guide at a point remote from the throat so that the button piece may flex readily to permit the requisite upward movement of the buttonhole fly. Preferably, the buttonholes are raised to proper button receiving position by swinging the feeding finger 70 upwardly as it approaches the end of its feeding movement, and, to this end, the stud shaft 60 is provided with an 70 arm 82 carrying an idler roll 84 riding on a cam 86 fixed to the upper surface of the table 6, the arrangement of the parts being such that upon the forward movement of the arm 65, the roll 84 is carried into engagement with a raised portion of the cam 86 to cause the feeding finger 70 to be elevated to the proper degree, whereas, upon the rearward movement of the arm 65, the roll 84 is upheld somewhat from the most depressed 80 portion of the cam 86 by the engagement of the plate 76 with the edge of the buttonhole fly.

The finger 70 for feeding the buttonhole fly is so constructed as to retain its engagement with a buttonhole of the fly which it enters on its rearward movement, and the fingers 18 and 19 are retained in gripping engagement with the buttonhole fly until substantially the time when the finger 70 90 normally completes its rearward movement. It has been found in the use of this machine that, when the buttons on the button piece of a shoe are inserted in the button guide, the buttonhole fly normally occupies substantially the proper position relatively to the button guide and its associated parts. There is, however, a slight tendency of the buttonhole fly to sag, increasing as the buttoning operations progress toward the top 100 of a shoe. The fly is supported against this tendency by the fingers 18 and 19 while it is gripped thereby and is at other times supported by the finger 70. Manifestly, the less the distance by which the buttonholes of a buttonhole fly are spaced from each other, the earlier in its rearward movement will the finger 70 enter a buttonhole, so that if the buttonholes in the fly being operated upon were spaced from each other by a distance less than the interval of movement of the finger 70 and the finger was positively operated on its rearward movement, the buttonhole might be torn by the finger 70 before the release of the fly by the fingers 18 and 19. In order to adapt the machine to operate on work in which the buttons and buttonholes are variously spaced, I provide means for operating the arm 65 carrying the finger 70, which will permit the 110

115

120

125

130

movement of the arm to be suspended after the engagement of the finger in a buttonhole until the fingers 18 and 19 are withdrawn from gripping engagement with the 5 buttonhole fly. Preferably, the operating means is constructed to move the arm 65 positively in the direction to feed the buttons and the buttonhole fly. As shown, such means comprises an arm 88 extending from 10 the hub of the arm 65 and having a bell-crank lever 90 pivoted thereto at 92 and connected by a link 94 with the free end of a lever 96 fulcrumed on a stud 98 mounted in the yoke 267. Motion is imparted 15 to the arm 96 by an idler roll 102 received in the peripheral groove of a cam 104 on the cam shaft 41. The lever 90 has a stud 106 extending upwardly therefrom and received in a slot in a member 108 pivoted 20 at one end to the table 6 and having its free end normally held in a predetermined position by a spring 110 connected to the member 108 and a stop pin 112. The slot of the member 108 is substantially concentric with the axis of the arms 88 and 65. 25 Consequently, since movement of the member 108 is prevented by the pin 112 upon movement of the link 94 in a direction to feed the buttons and the buttonhole fly, such movement is positively communicated to the 30 arms 88 and 65 substantially as if the link 94 were directly connected to the arm 88. When, however, upon the rearward movement of the arm 65, the finger 70 engages 35 a buttonhole of the buttonhole fly prior to the completion of the return movement of the link 94, the continued movement of the link 94 will serve merely to turn the bell-crank lever 90 about its pivot 92 against 40 the resistance of the spring 110, thus permitting the movement of the arm 65 and finger 70 to be suspended so long as the fly is gripped by the fingers 18 and 19. When 45 the buttonhole fly is released by the fingers 18 and 19, the arm 65 and finger 70 complete their return movement under the control of spring 110.

Means is provided for disengaging the finger 70 from a buttonhole of the buttonhole fly previous to the insertion of a button in the buttonhole. A preferred embodiment of such means comprises a wiper 114 formed integrally with the pusher 17 and adapted for engagement with a lug 116 55 projecting rearwardly from the finger 70. The pusher 17 and the wiper 114 are operated by an arm 118 projecting from the hub of the pusher and connected by a link 120 with a lever 122 fulcrumed also in the 60 yoke 267 and operated by a cam 124 on the cam shaft 41. The movement of the finger 19 across the slot of the button guide to open the buttonhole tends to disengage the buttonhole fly from the finger 70, the inward 65 movement of which is limited by the plate

76. The fin 80 on the plate 76, however, by contact with the inner surface of the fly adjacent to the inturned hooked end of the feeding finger projecting through the buttonhole maintains the fly on the finger until the finger is positively withdrawn from the buttonhole by the wiper 114. With this construction, the buttonhole is retained in proper button receiving position by the finger 70 until the gripping fingers 18 and 19 have taken a firm hold on the fly.

The machine is driven from a shaft 125 journaled in standards 126 projecting upwardly from the bottom plate 2 of the machine frame, and loosely mounted on the shaft 125 is a pulley 127 to which motion is transmitted from any suitable source of power. The pulley 127 may be clutched to the drive shaft 125 by any suitable means, but, as shown, such means comprises a member 224 keyed to the shaft and having a pin 128 adapted to be interposed in the path of movement of a pin 129 carried by the pulley 127. The clutch pin 128 is normally maintained by a spring or the like (not shown) 30 in a position to connect the pulley 127 operatively to the drive shaft. A wedge-shaped cam 130 on the pin 128 which is slidable in the clutch member 224 operates upon engagement with the end of a rod 134 35 to disconnect the clutch member and drive shaft 125 from the pulley 127 by laterally displacing the pin 128. The rod 134 is preferably mounted for sliding movement in standards 136 and 138 upstanding from the bottom plate 2 of the machine frame and is provided with a collar 140, between which and the standard 136 is interposed a spring 142 tending normally to move the end of the rod 134 into engagement with the cam 130 40 of the clutch member 224 to disengage the pulley 127 from the drive shaft. The clutch mechanism is manually actuated to start the machine by means preferably including a treadle (not shown) connected by a rod 144 45 to the free end of a lever 146 pivoted on the bottom plate 2 of the machine frame by a stud 147 journaled in standards 148 on the plate 2. A latch 150 is pivotally secured to the arm 146 at 152 and is provided with an 50 upstanding lug for engagement with a lug projecting laterally from a lever 154 also journaled on the stud 147 and adapted for engagement with the forward end of the collar 140 of the rod 134 to withdraw the 55 end of rod 134 from engagement with the clutch member 224 to initiate the operation of the machine. The machine is designed to be stopped independently of the release of the treadle by the operator. Accordingly, 60 a stop 156 on the bottom plate 2 is disposed to engage the tail of the latch 150 upon the depression of the arm 146, thereby moving the lug on the latch 150 downwardly against the tension of a spring 158 connected to the 65

latch and to the standard 138 to release the lever 154 from the control of the latch, said lever when thus released being moved forwardly out of engagement with the collar 140 on the rod 134 by a spring 160 interposed between the rearward arm of the lever and a boss on the bottom plate 2 (see Fig. 13).

As hereinbefore indicated, means is provided for controlling the clutch mechanism constructed to discontinue the operation of the machine after the performance of a predetermined number of buttoning operations. Such controlling means comprises an arm 162 pivoted to the standard 164 on the bottom plate 2 and adapted to be moved into engagement with the forward end of the collar 140 on the rod 134 (see Fig. 13), when such rod is withdrawn by actuation of the treadle rod 144, by a spring 166 disposed between a lug 168 projecting from the hub of the arm 162 and a second lug 170 extending laterally from the standard 164. With this construction, it is apparent that the operation of the machine will be discontinued upon movement of the arm 162 out of engagement with the collar 140 on rod 134 (see Fig. 14). A second arm 172 extends upwardly from the hub of the member 162 and carries an idler roll 174 adapted for engagement with an actuator sleeved on the shaft 125. As shown, the actuator comprises a cam 176 formed integrally with a ratchet wheel 178 and loose on the shaft 125. The ratchet wheel 178 is actuated by a pawl 180 on an arm 182 fulcrumed on the bottom plate 2 for movement with a second arm 183 held against a cam 184, which is fixed on the drive shaft 125, by a spring 185 connected to the bottom plate 2 and to an arm 186 fixed to the arms 182 and 183. Inasmuch as the cam 184 is constructed to actuate the arm 182 and pawl 180 once upon each rotation of the shaft, it results that the number of rotations of the drive shaft 125 before its operation is suspended, and, consequently, the number of buttoning operations performed by the machine is determined by the number of step by step movements necessary to be imparted to the ratchet wheel 178 and cam 176 before the arm 172 is actuated by the raised portion of the cam 176 to lift the arm 162 out of engagement with the rod 134. The cam 176 is, in the illustrated construction, positioned by a stop 188 engaged by a lug 190 extending laterally from the ratchet wheel 178. In order that the machine may be set to perform a variable number of buttoning operations, the stop 188 is made adjustable. As shown, it constitutes an extension of a tooth of a pinion 192 mounted loosely on the drive shaft 125 and meshing with a segmental gear 194 on a stud shaft 196 journaled in one of the uprights 126. The stud shaft 196

carries an indicator arm 198 co-acting with an indicator plate 200, which is provided with numerals to indicate the number of buttoning operations which will be performed by the machine when the indicator arm is set in any of its various positions of adjustment. The indicator arm 198 is, for convenience, in setting the clutch controlling means, formed as a handle for manipulation by the operator. Retrograde movement of the ratchet wheel 178 and cam 176 is normally prevented by a detent 204 on the arm 172. When, however, the arm 172 is actuated by the cam 176 to discontinue the operation of the machine, a pin 206 (see Fig. 13) carried by the arm and lying beneath the pawl 180 elevates the pawl out of engagement with the ratchet wheel 178. Inasmuch as the detent 204 is carried out of engagement with the ratchet wheel by this same movement of the arm, the cam 176 is free to be returned to set position as determined by the stop 188. A volute spring 207 coiled in a recess of the actuator between the cam 176 and ratchet wheel 178 effects the return movement of the cam and thus automatically resets the clutch controlling mechanism upon the completion of each series of operations for which the machine is set.

Access may be had to the operating mechanism of the machine by removing the screw 222 which secures the link 30 to the arm 28 carried by the hub 23 of the finger 19 and then raising the cover 6 about its pivots in the uprights 4. The cover is provided with a hook (not shown) arranged to coact with a second hook 223 (see Fig. 12) rising from the bottom plate 2 to limit the backward movement of the cover after it has been carried beyond a vertical position.

The motion of the drive shaft 125 is transmitted to the cam shaft 41 by a gear 208 on the drive shaft meshing with an idler gear 210 which is in turn intergeared with a gear 212 sleeved loosely on the cam shaft 41. The gear 212 is normally clutched to the cam shaft by a member 214 urged outwardly into an internal groove 215 in the gear 212 by a spring 216 and pivoted to a pin 217 received in a bore of the shaft and provided with a handle 218. The clutch member 214 has an inclined surface 220 which causes the member 214 to be moved out of engagement with the groove of the gear 212 when the pin 217 is drawn outwardly by manipulation of the handle 218. It will be obvious that the operation of the buttoning instrumentalities may be suspended at any time by the disconnection of the gear 212 from the cam shaft. For example, if the indicator 198 is set to discontinue the operation of the machine after the performance of eight buttoning operations, its operation may, nevertheless, be suspended after the performance of one or

two of any number of operations less than eight by the pulling out of the pin 217 by the handle 218. Moreover, the buttoning instrumentalities may be manually operated, 5 when desired, by pulling out the pin 217 and turning the handle 218.

The manner of operation of the machine will, it is believed, be readily comprehended from the foregoing description but may be 10 briefly summarized as follows: Assuming that a right shoe is to be buttoned, the buttons on the button fly are, as hereinbefore pointed out, introduced into the slot 10 of the button guide 8, beginning with the 15 throat button. The machine stops with the button feeder 58 and the finger 70 for feeding the buttonhole fly at their rearward limits of movement. The operator moves the shoe forward until the throat button is 20 carried into the recess of the button feeder and inserts the finger 70 in the corresponding buttonhole of the buttonhole fly (see Figs. 4 and 5). Upon the initiation of the 25 operation of the machine, the arm 65 is moved forward carrying with it the button feeder 58 and the finger 70 thereby feeding the button toward the delivery end of the slot 10 and moving the buttonhole fly to 30 present the buttonhole engaged by the finger 35 in position to receive the button from the guide. As the finger 70 passes through the final portion of its feeding movement, it is raised by operation of the cam 86 on the arm 82 of the shaft 60 so as to carry the 40 upper edge of the buttonhole slightly above the crown of the button, the parts being then in the positions shown in Fig. 6. Just prior to the completion of the feeding movement of the button feeder 58 and finger 70, 45 the fingers 18 and 19 begin their inward movement to grip the buttonhole fly rearwardly and forwardly of the buttonhole against the button guide and the member 20 respectively, the movement of the finger 50 19 being continued after the gripping of the buttonhole piece by the fingers 18 and 19, thereby moving the forward edge of the buttonhole and the material surrounding the buttonhole across the slot 10 and trans- 55 versely of the body of the fly to open the buttonhole and thrusting the member 20 away from the slot 10 of the button guide. The forward movement of the pusher 17 is initiated substantially at the same time that 60 the fingers 18 and 19 begin to move in. As the pusher advances, its end impinges against the upwardly curved surface 169 of the button feed lever 58 and elevates the lever from the button, which is engaged by 65 the pusher substantially simultaneously with the completion of the movement of the finger 19. The parts are then in the positions shown in Figs. 9 and 10. The opening of the buttonhole by the finger 19 tends to 70 carry the buttonhole off the finger 70 which is

fully withdrawn from the buttonhole by the operation of the wiper 114 against the lug 116 on the finger 70 upon the continued movement of the pusher 17. Simultaneously with the disengagement of the finger 70 from the 70 buttonhole, the arm 65 begins its rearward movement thus withdrawing the finger from the plane of the buttonhole. The pusher 17 first engages the side of the button, but as the button enters the buttonhole, it is turned 75 about its point of attachment to the button piece, the point of contact of the end of the pusher therewith moving gradually away from the apex of the button until, after the button has been turned through an angle of 80 substantially 90°, the end of the pusher engages the under surface of the button, as shown in Fig. 8. As the movement of the pusher 17 continues, the button is moved outwardly beyond the edges of the buttonhole and the work engaging end of the buttonhole opening finger 19. By reason of 85 its attachment to the button piece, the button moves downwardly at the same time that it is carried outwardly by the pusher 17 in 90 consequence of which the end surface of the pusher passes above the button and further movement of the pusher causes its end to be projected between the button and the edge of the buttonhole. It will be understood 95 from the foregoing that there is imparted to the pusher a movement additional to that ordinarily required to pass a button into a buttonhole. Such additional movement insures the complete insertion of the buttons. 100 The rearward movement of the arm 65 is continued after the insertion of the first button in its corresponding buttonhole to cause the button feed lever 58 to engage the next adjacent button on the button piece and the 105 feeding finger 70 to enter the next buttonhole of the buttonhole fly, the proper entry of the finger 70 into the buttonhole being assured by the controlling plate 76 which 110 determines the spacing of the end of the finger from the edge of the buttonhole fly. If the finger 70 enters a buttonhole of the buttonhole fly before it has completed its rearward movement, its movement will be 115 suspended until the buttonhole fly is released by the grippers 18 and 19. In such a case, the finger 70 completes its rearward movement under control of spring 110 while the fingers 18 and 19 are being retracted, during which time the member 20 is again 120 projected across the slot 10 of the button guide by its spring 50, and the pusher 17 and wiper 114 are withdrawn. The machine is then ready to begin the operation of buttoning the second button.

Inasmuch as the buttons on a left shoe are curved oppositely to those on a right shoe, a left shoe will occupy a reversed position in the machine from that of a right shoe, that is, the buttons nearest the top of 130

the button fly will be first introduced into the slot of the guide and the toe of the shoe will extend toward the loop 11 of the guide instead of toward its delivery end. Accordingly, the buttoning of the final buttons on a left shoe, that is, the buttons on the lower part of the button piece adjacent to the vamp, causes the toe of the shoe to engage the under surface of the guide. Assuming that one of the buttons near the lower part of the button fly, for example, the fourth from the vamp is being buttoned, by reason of the concave curvature of the top of the instep and the toe of the shoe and the engagement of the toe of the shoe with the button guide, the buttons intermediate between the fourth button and the vamp will normally lie below a line joining the delivery end of the guide with the point of the guide engaged by the toe of the shoe. If, therefore, the button guide were made straight, considerable strain would be imposed on the buttons adjacent to the vamp. Moreover, the buttonhole piece which is not controlled so positively as the buttons in the guide would tend to follow the natural curvature of the shoe and the corresponding buttonholes of the piece might, therefore, be disposed so far below the normal level of the buttonholes as not to be engaged by the finger 70. In order to avoid the difficulties above mentioned, the depression 12 of the button guide is made to conform substantially with the curvature of the shoe so that no appreciable strain is imposed on the buttons intermediate between the one being operated upon and the vamp and the corresponding buttonholes are positioned at the level of the guide in position for engagement by the finger 70 which moves substantially in line with the guide.

If, for example, it is desired to button seven buttons, the indicator arm 198 will be set to register with the numeral 7 on the indicator plate 200. The stop 188 will then be positioned so as to require seven step by step movements of the ratchet wheel 178 and cam 176 to bring the raised portion of the cam 176 beneath the arm 172 to elevate the arm 162 from engagement with the rod 134 so as to stop the machine. The pawl 180 which operates the ratchet wheel is actuated by the cam 184 once upon each revolution of the drive shaft 125 and the buttoning instrumentalities are caused to perform a buttoning operation on each rotation of the shaft. Consequently, the operation of the buttoning instrumentalities will be discontinued after the performance of seven buttoning operations. When the arm 172 is actuated to stop the machine, the pin 206 on the arm elevates the pawl 180 from engagement with the ratchet wheel 178 and the detent 204 is lifted away from the ratchet wheel, whereupon the spring 207 returns the ratchet

wheel 178 and cam 176 to set position. Consequently, if the position of the indicator arm 198 remains unchanged and the treadle rod 144 is depressed, the machine will perform a second series of seven buttoning operations, after which the operation of the machine will again be discontinued.

The machine in which the invention is herein shown as embodied is adapted to operate on work of widely different characteristics without adjustment or substitution of parts. For example, it is unnecessary to substitute button guides having slots of different curvatures even when the curvatures of the lines of buttons in the button piece vary greatly inasmuch as the flexibility of the button piece permits the buttons to be inserted into the slot of the guide irrespective of the degree of curvature of the line of the buttons. Moreover, as hereinbefore indicated, the feeding means for the buttons and the buttonhole fly automatically accommodate themselves to variations in the spacing of the buttons and buttonholes either in the same or in different pieces of work. The button feeder disclosed herein is designed particularly for feeding round-headed buttons, such as are commonly used on shoes. It is customary, however, to employ flat-topped buttons on gaiters, and in case the machine of my invention is to be used for buttoning gaiters having buttons of such character, the form of the button feeder is preferably modified to adapt it better for operation thereon. Moreover, if a machine is to be used for buttoning gaiters, it may be desirable not to depress the button guide adjacent to its delivery end as hereinbefore described.

Having described my invention, what I claim as new and desire to secure by Letters Patent of the United States is:—

1. In a buttoning machine, means for receiving a plurality of buttons on the button piece of a shoe and buttoning instrumentalities for inserting the buttons one by one into the buttonholes of the buttonhole fly constructed and arranged to button a plurality of buttons adjacent to the throat of the upper and including the throat button on a right or a left shoe.

2. In a buttoning machine, means for receiving a plurality of buttons on the button piece of a shoe and buttoning instrumentalities for moving the material of the button hole fly across the end of said button receiving means to permit the buttons adjacent to the throat of either a right or left shoe to enter the corresponding buttonholes.

3. In a buttoning machine, a button guide having a slot to receive a plurality of buttons on the button piece of a shoe, and means for positioning a buttonhole fly with the throat buttonhole beyond the end of said guide for reception of the throat button.

4. In a buttoning machine, a button guide having a slot to receive a plurality of buttons on the button piece of a shoe, and mechanism for buttoning the buttons adjacent to the throat of a shoe which is presented to the machine with the buttons nearest the upper edge of the buttonhole fly in advanced position in the slot of the guide, said mechanism constructed and arranged 10 to move the material of the buttonhole fly transversely across the end of said slot.
5. In a buttoning machine, the combination of a button guide having a slot to receive a plurality of buttons on a button piece, means for passing the buttons on the button piece successively into the buttonholes of a buttonhole fly, and means operable on the buttonhole fly at points adjacent to a buttonhole and oppositely disposed relatively to the buttonhole to restrain the fly from movement in the direction in which a button moves in entering the buttonhole.
6. In a buttoning machine, the combination of a pusher for passing the buttons on a button piece successively into the buttonholes of a buttonhole fly and fingers operable on the buttonhole fly along the opposite side edges of a buttonhole in the fly to restrain the buttonhole fly from movement in the direction in which a button moves in entering the buttonhole.
7. In a buttoning machine, means for passing a plurality of buttons on a button piece successively into the buttonholes of a buttonhole fly, means for feeding the buttons successively to the passing means, means for feeding the fly to present a buttonhole in position to receive a button, and means for clamping the fly to retain the buttonhole in such position.
8. In a machine for operating on shoe uppers, means for feeding a buttonhole fly, and means for clamping the fly at a point in advance of the forward limit of movement of the feeding means.
9. In a buttoning machine, the combination of a button guide having a slot to receive a plurality of buttons on a button piece, spaced members operable toward and from the guide adjacent to the delivery end of the slot, means for guiding a buttonhole fly intermediate between said members and the button guide, means for feeding the buttonhole fly to present the buttonholes of the fly successively intermediate between the paths of movement of said members, means for moving said members into engagement with the fly on opposite sides of the buttonholes successively, a movable member co-operating with one of said spaced members to carry the material adjacent the buttonholes across the end of the slot and means for passing the buttons on the button piece into the buttonholes of the fly.
10. In a buttoning machine, the combination of means for supporting a button, means for controlling a buttonhole fly and formed to present spaced surfaces disposed for engagement with the fly close to the opposite sides of a buttonhole in the fly intermediate between the ends of the buttonhole, and means for passing the button into the buttonhole.
11. In a buttoning machine, the combination with a button guide having a slot to receive a plurality of buttons on a button piece, of means for guiding a buttonhole fly in a plane substantially parallel to the axes of the buttons in the guide, and means for effecting relative movements of the button piece and the fly to pass the buttons on the button piece successively into the buttonholes of the fly.
12. In a buttoning machine, the combination with a button guide having a curved slot to receive a plurality of buttons on a button piece, of means for guiding a buttonhole fly in a curved path substantially parallel to the slot of the button guide, and means for manipulating the buttons and the fly to insert the buttons on the button piece into the buttonholes of the fly.
13. In a buttoning machine, mechanism for successively inserting a plurality of buttons on a button piece into the buttonholes of a buttonhole fly comprising a feeding member for the buttons and a pusher operable on the head of each of the buttons to pass it into the corresponding buttonhole.
14. In a buttoning machine, mechanism for successively inserting a plurality of buttons on a button piece into the buttonholes of a buttonhole fly comprising a guide having a slot to receive the buttons and a member constructed and arranged for engagement with the heads of the buttons to pass them into the buttonholes.
15. In a buttoning machine, buttoning instrumentalities comprising a member having movement of a character to push a button on a button piece into a buttonhole of a buttonhole fly and constructed and arranged to pass out of operative relationship to the button upon continuation of such movement after the button has entered the buttonhole.
16. In a buttoning machine, buttoning instrumentalities comprising a pusher for passing a plurality of buttons on a button piece successively into the buttonholes of a buttonhole fly, said instrumentalities being constructed and operated to insert the buttons completely into the buttonholes, and means for feeding the buttons one by one to the pusher.
17. In a buttoning machine, a button guide having a slot to receive a plurality of buttons on a button piece and means supported in its movement by the guide for passing the buttons on the button piece com-

pletely into the buttonholes of a buttonhole fly.

18. In a buttoning machine, a member for pushing a button on a button piece into a buttonhole of a buttonhole fly and operating means for the member constructed to move the button engaging end of the member into the buttonhole with its whole cross-sectional dimension interposed between the button and the edge of the buttonhole to insure the complete insertion of the button into the buttonhole.

19. In a buttoning machine, a button guide having a slot to receive a plurality of buttons on a button piece and a pusher co-acting with said guide for passing the buttons on the button piece into the buttonholes of a buttonhole fly by engagement with their heads, said pusher being constructed and arranged to turn the buttons about their points of attachment to the button piece.

20. In a buttoning machine, a button guide having a slot to receive a plurality of buttons on a button piece and a pusher movable angularly of said slot for passing the buttons on the button piece successively into the buttonholes of a buttonhole fly.

21. In a buttoning machine, the combination of a button guide having a slot to receive a plurality of buttons on a button piece, means for guiding a buttonhole fly in a plane substantially parallel to the axes of the buttons in the button guide, means for presenting the buttonholes of the fly successively at the delivery end of said slot, and means for passing the buttons on the button piece into the buttonholes of the fly.

22. In a buttoning machine, means for passing a button on a button piece into a buttonhole of a buttonhole fly, and means for opening the buttonhole comprising a finger disposed for engagement with one of the edges of the buttonhole and operable to prevent movement of said edge in the direction of movement of the button in entering the buttonhole so as to insure the complete introduction of the button into the buttonhole.

23. In a buttoning machine, buttonhole opening means comprising a member having a portion adapted for engagement with the edge of a buttonhole, and means for passing a button into the buttonhole past the edge of the buttonhole and the work engaging portion of said member.

24. In a buttoning machine, means for opening a buttonhole of a buttonhole fly comprising a member having its end positioned for engagement with the edge of a buttonhole and a pusher movable transversely of the buttonhole fly for passing a button into the buttonhole past the edge of the buttonhole and the end of said member.

25. In a buttoning machine, buttonhole

opening means comprising a member having a portion adapted for engagement with the edge of a buttonhole, and means for passing a button on a button piece into the buttonhole operable to turn the button about its point of attachment to the button piece and to move the entire head of the button beyond the edge of the buttonhole and the work engaging portion of said member.

26. In a buttoning machine, means for successively passing a plurality of buttons on a button piece into the buttonholes of a buttonhole fly, and means for opening the buttonholes of the fly by engagement with their edges, said means being constructed and arranged to remain in engagement with said buttonholes to keep them open and substantially unobstructed during passage of the buttons.

27. In a buttoning machine, means for successively passing a plurality of buttons on a button piece into the buttonholes of a buttonhole fly, means for feeding the fly, and means independent of the feeding means for the fly for opening the buttonholes.

28. In a buttoning machine, means for successively passing a plurality of buttons on a button piece into the buttonholes of a buttonhole fly, means for feeding the fly, and means movable transversely of the direction of feeding movement of the fly for opening the buttonholes.

29. In a buttoning machine, means for successively passing a plurality of buttons on a button piece into the buttonholes of a buttonhole fly, means for feeding the buttons one by one to the passing means, and means for opening the buttonholes of the fly operable to move one of the edges of the buttonholes transversely of the fly.

30. In a buttoning machine, means for successively passing a plurality of buttons on a button piece into the buttonholes of a buttonhole fly, means for feeding the fly, and means independent of the feeding means for moving one of the edges of the buttonholes transversely of the fly to open the buttonholes.

31. In a buttoning machine, the combination with a button guide having a slot to receive a plurality of buttons on a button piece, of means comprising a member movable substantially in the plane of the button guide for opening a buttonhole of a buttonhole fly, and means for passing a button from the guide into the buttonhole.

32. In a buttoning machine, the combination of a button guide having a slot to receive a plurality of buttons on a button piece, spaced members operable toward and from the guide adjacent to the delivery end of the slot, means for guiding a buttonhole fly intermediate between said members and the button guide, means for presenting the

buttonholes of the fly successively at the delivery end of said slot, means comprising said spaced members for opening the buttonholes, and means for passing the buttons 5 on the button piece into the buttonholes of the fly.

33. In a buttoning machine, the combination of a button guide having a slot to receive a plurality of buttons on a button 10 piece, spaced fingers operable toward and from the guide adjacent to the delivery end of the slot, means for guiding a buttonhole fly intermediate between said members and the button guide, a button feeder, a device 15 for feeding the fly to present the buttonholes successively at the delivery end of the slot, means for moving one of said fingers transversely of the delivery end of the slot to open the buttonholes, and means for passing 20 the buttons on the button piece into the buttonholes of the fly.

34. In a buttoning machine, the combination of a button guide having a slot to receive a plurality of buttons on a button 25 piece, means for guiding a buttonhole fly in a plane substantially parallel to the axes of the buttons in the button guide, means for successively moving one of the edges of the buttonholes transversely of the fly to open 30 the buttonholes, and means for passing the buttons of the button piece successively into the buttonholes of the fly.

35. In a buttoning machine, the combination of a button guide having a slot to receive a plurality of buttons on a button 35 piece, means for feeding a buttonhole fly to present the buttonholes of the fly successively at the delivery end of the slot, means for gripping the fly rearwardly of the buttonholes against the button guide, means for 40 moving the forward edges of the buttonholes transversely of the fly to open the buttonholes, and means for passing the buttons of the button piece into the buttonholes of the fly.

36. In a buttoning machine, the combination of a button guide having a slot to receive a plurality of buttons on a button 50 piece, means for positioning a buttonhole fly transversely of the plane of the button guide, and means for effecting relative movements of the buttons and the buttonhole fly to pass the buttons on the button piece successively into the buttonholes of 55 the fly.

37. In a buttoning machine, the combination of a button guide having a slot to receive a plurality of buttons on a button 60 piece, means for positioning a buttonhole fly transversely of the plane of the button guide, means for opening the buttonholes of the fly, and means for successively passing the buttons on the button piece into the buttonholes of the fly.

38. In a buttoning machine, the combina-

tion of a button guide having a slot to receive a plurality of buttons on a button piece, means for guiding a buttonhole fly relatively to the button guide, and a pusher movable angularly of the slot of the button 70 guide for passing the buttons on the button piece successively into the buttonholes of the fly.

39. In a buttoning machine, the combination of a button guide having a slot to receive a plurality of buttons on a button piece, means for guiding a buttonhole fly relatively to the button guide, means for opening the buttonholes of the fly successively, and means movable angularly of the slot of the button guide for passing the buttons on the button piece successively into the buttonholes of the fly.

40. In a buttoning machine, the combination with a button guide having a slot to receive a plurality of buttons on a button piece and having the wall on one side of the slot extended beyond the wall on the other side of the slot, means for guiding a buttonhole fly relatively to the button guide, and a pusher movable angularly of the slot for passing the buttons across the forward end of the shorter wall of the guide into the buttonholes of the fly.

41. In a buttoning machine, the combination with a button guide having a slot to receive a plurality of buttons on a button piece, means for guiding a buttonhole fly relatively to the button guide, a button feeder, a finger for feeding the fly to present the buttonholes of the fly at the delivery end of the slot, and a pusher movable angularly of the slot at its delivery end and operable to pass the buttons from the slot of the guide into the buttonholes of the fly.

42. In a buttoning machine, the combination of a button guide having a slot to receive a plurality of buttons on a button piece, means for guiding a buttonhole fly relatively to the button piece, means movable substantially in the plane of the button engaging surface of the button guide for gripping the fly at one side of a buttonhole, and means operable on the fly at the other side of the buttonhole to effect movement of such portion of the fly transversely of the main body of the fly to open the buttonhole, and means for passing a button into the buttonhole.

43. In a buttoning machine, the combination of a button guide having a slot to receive a plurality of buttons on a button piece, means for guiding a buttonhole fly relatively to the button piece, a finger movable substantially in the plane of the button engaging surface of the button guide for gripping the fly adjacent to one side of a buttonhole, and grippers for engaging the fly at the other side of the buttonhole, said grippers being movable across the slot of

the button guide to effect movement of the fly at such side of the buttonhole transversely of the main body of the fly to open the buttonhole, and a pusher for passing a button into the buttonhole.

44. In a buttoning machine, the combination of means for supporting a button, means for gripping a buttonhole fly on opposite sides of a buttonhole in the fly, said means comprising a member movable transversely of the fly to open the buttonhole, and means for passing the button into the buttonhole.

45. In a buttoning machine, means for opening a buttonhole of a buttonhole fly comprising a member adapted for engagement with the fly at one side of the buttonhole, a finger carried by said member for gripping the fly at the other side of said buttonhole, and means for passing a button into the buttonhole.

46. In a buttoning machine, the combination of a button guide having a slot to receive a plurality of buttons on a button piece, means for guiding a buttonhole fly relatively to the button piece, means for gripping the fly at one side of a buttonhole against the button guide adjacent to the delivery end of said slot, means movable across the end of the slot for opening the buttonhole, and means for passing a button into the buttonhole.

47. In a buttoning machine, the combination of a button guide having a slot to receive a plurality of buttons on a button piece, a yielding member disposed across said slot, yielding means for gripping a buttonhole fly rearwardly of a buttonhole against said guide, means for gripping the fly forwardly of the buttonhole against said yielding member and moving such portion of the fly and said yielding member transversely of said slot to open the buttonhole, and means for passing a button into the buttonhole.

48. In a buttoning machine, the combination with a button guide having a slot to receive a plurality of buttons, of means for gripping a buttonhole fly adjacent to one side of a buttonhole, and means operable on the fly at the other side of the buttonhole to effect movement of such side of the buttonhole transversely of the fly to open the buttonhole, and means for passing a button into the buttonhole.

49. In a buttoning machine, the combination with a button guide having a slot to receive a plurality of buttons, of means for opening a buttonhole of a buttonhole fly comprising a member normally positioned across the delivery end of said slot, and means for passing a button into the buttonhole.

50. In a buttoning machine, the combination with a button guide having a slot to

receive a plurality of buttons, of means for guiding a buttonhole fly relatively to the button guide, a member normally disposed across the slot of the button guide, means for gripping the fly adjacent to one side of a buttonhole against said member and moving the member and such portion of the fly across the slot of the button guide to open the buttonhole, and means for passing a button into the buttonhole.

51. In a buttoning machine, the combination with a button guide having a slot to receive a plurality of buttons on a button piece, of means for guiding a buttonhole fly in a plane substantially parallel to the axes of the buttons in said slot, a member normally disposed across the delivery end of the slot of the button guide and movable away from the slot, means for gripping the fly adjacent to one side of a buttonhole against said member and moving said member away from said slot to open the buttonhole, and means for passing a button into the buttonhole.

52. In a buttoning machine, the combination of a button guide having a slot to receive a plurality of buttons, a member for preventing the escape of the buttons from said slot, means for passing a button in the guide into a buttonhole of a buttonhole fly, and means co-acting with said member to open the buttonhole.

53. In a buttoning machine, the combination of a button guide having a slot to receive a plurality of buttons on a button piece, a member disposed transversely across the end of said slot to prevent the escape of the buttons from said slot, and means constructed and arranged for manipulation by the operator to move said member away from said slot to permit the removal of the buttons from the slot.

54. In a buttoning machine, a button holder, means for positioning a buttonhole fly relatively to the button holder with the long dimension of a buttonhole disposed throughout its entire extent substantially parallel to the axis of the button, and means for effecting relative movement of a button and the fly to pass the button into the buttonhole.

55. In a buttoning machine, the combination of a button guide having a slot to receive a plurality of buttons, of a guide for a buttonhole fly constructed to position a buttonhole of the fly with its long dimension disposed substantially parallel to the axis of a button in the guide, and means for passing a button into the buttonhole.

56. In a buttoning machine, buttoning instrumentalities including means for engaging and passing a button on a button piece into a buttonhole of a buttonhole fly, and means for feeding the button to said passing means.

57. In a buttoning machine, the combination with a button guide having a slot to receive a plurality of buttons, of a button feeder and a pusher separate from the button feeder for engaging the buttons and passing them into the buttonholes of a buttonhole fly. 65
58. In a buttoning machine, means for passing a plurality of buttons on a button piece successively into the buttonholes of a buttonhole fly, button feeding means, and means for feeding the fly operable in a plane offset laterally from the plane of operation of the button feeding means. 70
59. In a buttoning machine, a button guide having a slot to receive a plurality of buttons on a button piece, a button feeder movable substantially in the plane of the slot of the guide, and a finger for feeding a buttonhole fly operable in a plane offset from the slot of the guide. 75
60. In a buttoning machine, means for passing a plurality of buttons on a button piece successively into the buttonholes of a buttonhole fly, and feeding means for the button piece and the fly movable at substantially equal rates of speed. 80
61. In a buttoning machine, the combination with a button guide having a slot to receive a plurality of buttons, of means for feeding the buttons, means for feeding a buttonhole fly, and means separate from the button feeding means for passing the buttons into the buttonholes of the fly. 85
62. In a buttoning machine, a button guide having a slot to receive a plurality of buttons on a button piece, means for guiding a buttonhole fly relatively to the button piece, means for feeding the buttons, means for feeding the fly, and common operating means for the button feeding means and the feeding means for the fly. 90
63. In a buttoning machine, a button guide having a slot to receive a plurality of buttons on a button piece, means for guiding a buttonhole fly relatively to the button piece, means for feeding the buttons, means for feeding the fly, an arm upon which the button feeding means and the feeding means for the fly are mounted, and means for operating said arm. 95
64. In a buttoning machine, means for inserting a plurality of buttons on a button piece into the buttonholes of a buttonhole fly, an arm, members carried by said arm for feeding the buttons and the fly, means for operating the arm to impart feeding movement to said members, and means for effecting relative movement of said feeding members. 105
65. In a buttoning machine, means for inserting a plurality of buttons on a button piece into the buttonholes of a buttonhole fly, an arm, members carried by said arm for feeding the buttons and the fly, means for operating the arm to impart feeding movement to said members, and means for effecting relative movement of said feeding members. 110
66. In a buttoning machine, mechanism for successively inserting a plurality of buttons on a button piece into the buttonholes of a button hole fly, and means for feeding the buttons to the inserting means by engagement with their heads. 115
67. In a buttoning machine, mechanism for successively inserting a plurality of buttons on a button piece into the buttonholes of a buttonhole fly and comprising a button guide having a slot to receive the buttons and means for feeding the buttons in the slot of the guide by engagement with their heads. 120
68. In a buttoning machine, mechanism for successively passing a plurality of buttons on a button piece into the buttonholes of a buttonhole fly, means for feeding the buttons to the passing mechanism, and means for disengaging the feeding means from the buttons. 125
69. In a buttoning machine, mechanism for successively inserting a plurality of buttons on a button piece into the buttonholes of a buttonhole fly and comprising means for feeding the buttons by engagement with their heads and means for lifting the feeding means to disengage it from the heads of the buttons. 130
70. In a buttoning machine, mechanism for successively inserting a plurality of buttons on a button piece into the buttonholes of a buttonhole fly, comprising a button feeder and a pusher for disengaging the buttons from the feeder and passing them into the buttonholes. 135
71. In a buttoning machine, the combination with a button guide having a slot to receive a plurality of buttons, of means for guiding a buttonhole fly relatively to the button guide, means for feeding the fly, and means for controlling the feeding means for the fly constructed and arranged for engagement with the fly. 140
72. In a buttoning machine, the combination with a button guide having a slot to receive a plurality of buttons, of means for guiding a buttonhole fly relatively to the button guide, means constructed and arranged for engagement with the buttonholes of the fly to feed the fly, and means positioned by the fly for controlling the movements of the feeding means for the fly. 145
73. In a machine for operating on shoe uppers the combination of means for guiding a buttonhole fly, a finger for feeding the fly by engagement with the buttonholes of

the fly and a controller for spacing the end of the finger at a predetermined distance from the edge of the fly.

74. In a buttoning machine, the combination with a button guide having a slot to receive a plurality of buttons on a button piece, of means for guiding a buttonhole fly relatively to the button guide, means for feeding the fly by engagement with the buttonholes of the fly, and a controller constructed for engagement with the edge of the fly to space the feeding means for the fly by a predetermined distance from its edge.
75. In a buttoning machine, means for passing the buttons on a button piece successively into the buttonholes of a buttonhole fly, and means for raising the fly to present a buttonhole of the fly in position to receive a button.

76. In a buttoning machine, means for passing the buttons on a button piece successively into the buttonholes of a buttonhole fly and mechanism constructed and arranged to feed the fly intermittently and to move the fly upon each feeding movement in a direction transverse to its feeding movement to present the buttonholes of the fly successively in button receiving position.

77. In a buttoning machine, the combination with a button guide having a slot to receive a plurality of buttons on a button piece, of means for guiding a buttonhole fly relatively to the button guide, means for moving a button from the button guide into a buttonhole of the fly, and means for raising the fly to position the buttonhole relatively to the button moving means to facilitate the insertion of the button into the buttonhole.

78. In a buttoning machine, the combination with a button guide having a slot to receive a plurality of buttons on a button piece, of means for guiding a buttonhole fly relatively to the button guide, means at the delivery end of said slot for inserting the buttons of the button piece into the buttonholes of the fly, and means for feeding the fly to carry the button holes of the fly into operative relation with said inserting means constructed and arranged to elevate the buttonholes of the fly at the delivery end of said slot to facilitate the insertion of the buttons into the buttonholes.

79. In a buttoning machine, the combination with a button guide having a slot to receive a plurality of buttons on a button piece, of means for guiding a buttonhole fly relatively to the button guide, means at the delivery end of said slot for inserting the buttons on the button piece into the buttonholes of the fly, and a feeding finger constructed for engagement with the buttonholes of the fly and operable to elevate the fly adjacent to the delivery end of the slot

to facilitate the insertion of the buttons into the buttonholes.

80. In a buttoning machine, the combination of a button guide having a slot to receive a plurality of buttons on a button piece, means for guiding a buttonhole fly in a plane substantially parallel to the axes of the buttons in the slot of the button guide, means for feeding the fly by engagement successively with the buttonholes of the fly, and yielding means tending normally to move the feeding means for the fly into engagement with the fly.

81. In a buttoning machine, the combination of a button guide having a slot to receive a plurality of buttons on a button piece, means for guiding a buttonhole fly in a plane substantially parallel to the axes of the buttons in the button guide, means for feeding the fly by engagement with the buttonholes of the fly, means adjacent to the delivery end of the slot of the button guide for passing a button on the button piece into a buttonhole of the fly, and cam means for operating the feeding means for the fly upwardly adjacent to the delivery end of the slot to position the buttonhole with its upper end spaced above the crown of the button to facilitate the insertion of the button into the buttonhole.

82. In a buttoning machine, mechanism for successively inserting a plurality of buttons on the button piece of a shoe into the buttonholes of the buttonhole fly comprising feeding means for the buttonhole fly operable to support the buttonhole fly.

83. In a buttoning machine, mechanism for successively inserting a plurality of buttons on a button piece into the buttonholes of a buttonhole fly comprising a finger adapted to project into a buttonhole of the fly and operable to support the fly.

84. In a machine for operating on shoe uppers, a guide for a buttonhole fly, means for spacing the fly from the guide, and feeding means for the fly constructed to pass through a buttonhole of the fly into contact with the guide.

85. In a buttoning machine, a button guide having a slot to receive a plurality of buttons on a button piece and having an upstanding portion at one side of said slot, means for passing the buttons on the button piece successively into the buttonholes of a buttonhole fly, and means operable along the side of said upstanding portion opposite from said slot for feeding the fly.

86. In a buttoning machine, mechanism for successively inserting buttons on a button piece into the buttonholes of a buttonhole fly and comprising a button guide having a slot to receive a plurality of buttons on a button piece, a member disposed substantially at right angles to the plane of the button guide for guiding the fly, means

- for spacing the fly from said parts, and means for feeding the fly arranged to project through a buttonhole of the fly into contact with one of said parts.
5. 87. In a buttoning machine, mechanism for successively inserting buttons on a button piece into the buttonholes of a button-hole fly and comprising means for guiding a buttonhole fly, a finger for feeding the fly by engagement with a buttonhole of the fly, a controller for the finger, and a part on the controller for spacing the fly from the guiding means.
10. 88. In a buttoning machine, mechanism for successively inserting buttons on a button piece into the buttonholes of a button-hole fly and comprising means for guiding a buttonhole fly, means for feeding the fly, means for urging the feeding means toward the guiding means, and means for limiting the movement of the feeding means toward the guiding means.
15. 89. In a machine for operating on shoe uppers, a guide for a buttonhole fly, a finger for feeding the buttonhole fly by engagement with the buttonholes of the fly, means for urging the finger toward the guide, and a controller operable to locate the work engaging portion of the finger at a predetermined distance from the edge of the fly and to limit the movement of the finger toward the guide.
20. 90. In a machine for operating on shoe uppers, means for feeding a buttonhole fly by successive engagement with the buttonholes of the fly, and means for maintaining the buttonhole fly against movement during movement of the feeding means from one buttonhole to another.
25. 91. In a buttoning machine, means for inserting a plurality of buttons on a button piece successively into the buttonholes of a buttonhole fly comprising feeding means for the buttonhole fly movable in one direction to feed the buttonhole fly and in the opposite direction to engage a fresh portion of the buttonhole fly, and means for retaining the buttonhole fly against movement during the last-mentioned movement of the feeding means.
30. 92. In a buttoning machine, means for passing a plurality of buttons on a button piece successively into the buttonholes of a buttonhole fly, a finger for feeding the fly, and means for moving the finger away from a buttonhole prior to the introduction of a button therein.
35. 93. In a buttoning machine, means for passing a plurality of buttons on a button piece successively into the buttonholes of a buttonhole fly, means for feeding the fly by engagement with the buttonholes of the fly, means for operating the feeding means, and means separate from said operating
- means for removing the feeding means from the buttonholes.
40. 94. In a buttoning machine, a pusher for passing a plurality of buttons on a button piece successively into the buttonholes of a buttonhole fly, a finger for feeding the fly by engagement with the buttonholes of the fly, and means carried by the pusher for removing the finger from the buttonholes.
45. 95. In a buttoning machine, means for successively inserting a plurality of buttons on a button piece into the buttonholes of a buttonhole fly comprising means for feeding the fly by engagement with a buttonhole of the fly constructed and arranged to retain its engagement with a buttonhole which it has once entered until the button-hole is presented in button receiving position.
50. 96. In a buttoning machine, means for successively inserting a plurality of buttons on a button piece into the buttonholes of a buttonhole fly comprising means for feeding the fly by engagement with the buttonholes of the fly, and means for operating the feeding means forwardly and rearwardly, said feeding means being constructed and arranged to retain its engagement with a buttonhole which it enters on its rearward movement until after a subsequent forward movement.
55. 97. In a machine for operating on shoe uppers, means for feeding a buttonhole fly by engagement with the buttonholes of the fly, means for operating the feeding means through a distance equal to the maximum spacing of the buttonholes, and means for gripping the fly operable to release the fly substantially simultaneously with the completion of the rearward movement of said operating means, the operating means being constructed and arranged to permit the movement of the feeding means to be suspended upon its engagement with a button-hole prior to the completion of its rearward movement and to continue the movement of the feeding means after the release of the fly by the gripping means.
60. 98. In a buttoning machine, means for successively inserting a plurality of buttons on a button piece into the buttonholes of a buttonhole fly comprising means for feeding the fly controlled by the fly.
65. 99. In a buttoning machine, means for successively inserting a plurality of buttons on a button piece into the buttonholes of a fly comprising means for gripping the fly, and means for feeding the fly constructed to move the fly rearwardly after release of the fly by the gripping means.
70. 100. In a buttoning machine, means for successively inserting a plurality of buttons on a button piece into the buttonholes of a buttonhole fly comprising gripper

- members operable to engage and support the fly, and a finger for feeding the fly adapted to engage the fly prior to its release by the grippers and constructed to 5 support the fly while free of the grippers.
101. In a machine for operating on shoe uppers, the combination of means for feeding a buttonhole fly by engagement with the buttonholes of the fly, and mechanism for 10 moving the feeding means positively in a direction to feed the work and for moving it yieldingly in the opposite direction to permit the movement of the feeding means to be arrested upon engagement of the feeding 15 means with a buttonhole of the fly previous to the completion of the reverse movement of the feeding means to compensate for variations in the spacing of the buttonholes.
102. In a buttoning machine, the combination of means for passing a button into a buttonhole of a buttonhole fly, an arm, work feeding means mounted on the arm, means for operating the arm, and a yielding connection between the arm and its operating 25 means.
103. In a buttoning machine, the combination of means for effecting relative movement between the buttons on a button piece 30 and a buttonhole fly to pass the buttons into the buttonholes of the fly, means for feeding the buttonhole fly by engagement with the buttonholes, means for operating the feeding means, and a yielding connection 35 between the feeding means and its operating means constructed and arranged to permit the movement of the feeding means to be arrested when it engages a buttonhole.
104. In a machine for operating on shoe 40 uppers, the combination of means for feeding a buttonhole fly by engagement with the buttonholes of the fly and means for operating the feeding means comprising a member loosely connected to the feeding 45 means and devices for maintaining said member against movement relatively to the feeding means upon movement of the operating means in a direction to feed the fly, said devices being constructed to permit 50 movement of said member relatively to the feeding means during reverse movement of the feeding means to allow the movement of the feeding means to be arrested upon engagement of said means with a buttonhole 55 of the fly previous to the completion of the reverse movement of said means.
105. In a machine for operating on shoe uppers, an arm, operating means for the arm comprising a member loosely connected 60 to the arm, and means for preventing movement of said member relatively to the arm upon movement of the operating means in one direction but constructed to permit movement of the member relatively to said 65 arm upon movement of the operating means in the opposite direction.
106. In a machine for operating on shoe uppers, an arm mounted for swinging movement, operating means for the arm comprising a member pivoted to the arm, and 70 mechanism for preventing movement of said member relatively to the arm upon movement of said operating means in one direction, said mechanism comprising an element having a slot substantially concentric with 75 the axis of said arm and being movable to permit movement of said member relatively to said arm upon movement of the operating means in the opposite direction.
107. In a buttoning machine, means for 80 successively inserting the buttons on a button piece into the buttonholes of a buttonhole fly comprising a button guide having a curved depressed portion constructed and arranged to relieve the tension of the work. 85
108. In a buttoning machine, means for effecting relative movement between the buttons on a button piece and a buttonhole fly to pass the buttons into the buttonholes of the fly, and a button guide having a curved 90 slot to receive the buttons on a button piece and being formed with a depressed portion to permit right and left shoes to be interchangeably buttoned.
109. In a machine of the class described, 95 the combination of a button guide having a slot to receive a plurality of buttons on a button piece and having a depressed portion, a pusher for successively passing the buttons from the button guide into the buttonholes of a buttonhole fly, and a feeding finger for the fly movable in a path substantially parallel to and in line with the depressed portion of the guide. 100
110. In a machine of the class described, 105 means for successively inserting buttons on a button piece into buttonholes of a buttonhole fly comprising a button guide having a depressed portion adjacent to its delivery end. 110
111. In a machine of the class described, 115 the combination of a button guide having a slot to receive a plurality of buttons on a button piece and having a depressed portion adjacent to its delivery end and means co-operating with the button guide at its delivery end for passing the buttons on the button piece successively into the buttonholes of a buttonhole fly. 120
112. In a buttoning machine, means for buttoning a plurality of buttons successively, means for operating the buttoning means, and means for automatically discontinuing the operation of the buttoning means after the performance of a predetermined number 125 of buttoning operations.
113. In a buttoning machine, means for buttoning a plurality of buttons successively,

means for operating the buttoning means, and controlling means for the operating means constructed and arranged to discontinue automatically the operation of the 5 buttoning means after the performance of a predetermined number of buttoning operations and including means for varying the number of buttoning operations.

114. In a buttoning machine, means for 10 buttoning a plurality of buttons successively, means for operating the buttoning means, controlling means for the operating means which may be set to discontinue the operation of the buttoning means after the 15 performance of a predetermined number of buttoning operations, and means for automatically resetting the controlling means.

115. In a buttoning machine, means for 20 buttoning a plurality of buttons successively, means for operating the buttoning means, controlling means for the operating means which may be set to discontinue the operation of the buttoning means after the 25 performance of a predetermined number of buttoning operations, and means for indicating the number of buttoning operations, for which the machine is set.

116. In a buttoning machine, a button 30 guide to receive a plurality of buttons on the button piece of a shoe, and means for successively positioning the buttonholes of a buttonhole fly at the end of the button guide with the long dimension of each buttonhole substantially parallel to the button 35 axis to receive the corresponding button.

117. In a buttoning machine, a button 40 guide to receive a plurality of buttons on the button piece of a shoe, and means for successively moving the material surrounding the buttonholes of a buttonhole fly transversely across the end of said button guide to permit the buttons to enter the corresponding buttonholes.

118. In a buttoning machine, a button 45 guide to receive a plurality of buttons on the button piece of a shoe, and means for successively engaging the forward edge of the buttonholes of a buttonhole fly to open the buttonholes and to present the material surrounding the buttonholes across the delivery 50 end of said button guide to permit entry of the buttons.

119. In a buttoning machine, a button 55 guide to receive a plurality of buttons on the button piece of a shoe, means for successively positioning the buttonholes of a buttonhole fly across the end of said button guide, and means for successively moving the buttons forwardly about their point 60 of attachment to the button piece to facilitate their entry into the corresponding buttonholes.

120. In a buttoning machine, a button 65 guide for receiving a plurality of buttons on the button piece of a shoe, buttoning

means, and means for feeding the buttonholes of a buttonhole fly substantially at the level of the button guide to allow the shoe to hang clear of the guide in its passage to the buttoning means. 70

121. In a buttoning machine, means for guiding a plurality of buttons on the button piece of a shoe, means for feeding the buttonholes of the buttonhole fly substantially in the plane of the button guide and for 75 raising each buttonhole near the end of the button guide whereby the shoe may be fed to buttoning instrumentalities without straining the material.

122. In a buttoning machine, means for 80 guiding a plurality of buttons on the button piece of a shoe, means for feeding the buttonholes of a buttonhole fly substantially in the plane of the button guide, means for raising each buttonhole at the end of the 85 button guide, and means for moving the material about each buttonhole across the end of said button guide to receive the button.

123. In a buttoning machine, means for 90 receiving a plurality of buttons on the button piece of a shoe and comprising a button guide having a depressed portion near its delivery end to facilitate the feeding of the throat portion of a shoe to buttoning 95 instrumentalities.

124. In a buttoning machine, means for 100 feeding a buttonhole fly by engagement with the buttonholes, said means constructed and arranged to lift a buttonhole at the end of each feeding movement, and means to clamp the buttonhole fly in its raised position to insure the entry of the feeding means into the next buttonhole on the return stroke.

125. In a machine for operating on shoe 105 uppers, an operating tool, and means for controlling the intermittent feed of the upper to the tool, said means comprising a finger having a lost motion connection to its actuating means and constructed and arranged to enter successively a series of holes in the upper on its back stroke whereby the effective feed movements of the finger are varied in accordance with the spaces between successive holes. 110

126. In a machine for operating on shoe 115 uppers, an operating tool, and means for controlling the intermittent feed of the upper to the tool, said means comprising an arm, a work feeding member carried by the arm, means for actuating the arm, and a yielding connection between the arm and its actuating means. 120

127. In a machine for operating on shoe 125 upper, an operating tool, mechanism for causing relative feed movements of the operating tool and an upper in the direction of a line of buttonholes on a buttonhole fly, said mechanism comprising oscillating means constructed for variable feeding 130

movements and arranged to enter a button-hole on its back stroke and to remain in engagement with said buttonhole throughout the balance of the feeding movement 5 whereby the buttonhole fly is supported in position on the machine and the feed movements are controlled by the spacing of the buttonholes, and means for causing relative movements of the upper and the tool in another direction to perform successive operations on the upper.

128. In a buttoning machine, means for successively presenting the buttons on the button piece of a shoe in a buttonhole entering position, mechanism for successively positioning the buttonholes of a buttonhole fly in button receiving position with the long dimension of each buttonhole substantially parallel to the button axis, and 20 means for causing the buttons successively to enter the corresponding buttonholes.

129. In a buttoning machine, the combination of a button guide having a slot to receive a plurality of buttons on a button piece, means for feeding a buttonhole fly, means for passing a button on the button piece into a buttonhole of the fly, and means separate from the passing means for bearing against the fly at one side of the 25 buttonhole to support the fly in position and facilitate the passage of a button into the buttonhole of the fly.

130. In a buttoning machine, the com-

bination of a button guide having a slot to receive a plurality of buttons on a button piece, means for guiding a buttonhole fly relatively to the button guide, means for feeding the buttons and the buttonhole fly, means for passing a button on the button piece into a buttonhole of the fly, means for 35 gripping the fly against said guiding means, and means for pressing against the side of the buttonhole away from the point of application of said gripping means to hold the same securely in position for the entrance 40 of a button under the action of said passing means.

131. In a buttoning machine, the combination of a button guide having a slot to receive a plurality of buttons on a button piece, means for feeding the button piece comprising a spring pressed member arranged to engage the eye of a button, means for guiding a buttonhole fly relatively to the button guide, means for passing a button on the button piece into a buttonhole of the fly, means for gripping the fly against said guiding means, and means for pressing against the side of the buttonhole away 50 from the point of application of said gripping means to hold the same securely in position for the entrance of a button under the action of said passing means.

In testimony whereof I have signed my name to this specification.

LEWIS J. BAZZONI.
